FOOT ELEVATING DEVICE

William M. Scholl, Palm Springs, Calif.

Application June 26, 1941, Serial No. 399,775

18 Claims. (Cl. 12—142)

The improvements relate to shoes, and particularly to low shoes or oxfords, in which there is inserted or incorporated by cementing or otherwise an insert or insole for elevating the foot of the wearer at the instep and heel portion, or heel portion alone.

Devices of this kind have a corrective use for persons who through accident, deformity or disease have one leg shorter than the other or one foot raised above the other, but their principal use is for persons who wish to appear taller. Where an elevation of one inch or more is required the shoe should be specially constructed to accommodate the height increasing insert or build-up, and even when elevations of less than one inch and as low as five-eighths of an inch are produced, it is advisable to do so. This special construction usually consists in increasing the height of the counter of the shoe when it is manufactured, so that the heel and instep of the wearer will not be raised above the counter so far as to make the shoe likely to slip off in walking or running. But as various persons require various elevations in order to meet their demands, it is necessary for the shoe manufacturer and dealer to make and keep on hand a large stock of shoes having various counter elevations from one-half inch to as much as three inches, and this involves a very heavy cost. The extra price charged for such shoes is also an obstacle to their sale and use.

The present improvements are designed to provide a stature increasing or foot elevating device which can be worn in any ordinary ready-made shoe without requiring any change in the original construction, can be easily applied to such shoe and at a small expense for labor and materials, will give the necessary build-up, will prevent the wearer's foot from being exposed above the shoe and the shoe from slipping off, and will make it unnecessary for the manufacturer and dealer to make and keep in stock special shoes to accommodate different elevations in the various shoe sizes.

The improvements are illustrated in the accompanying drawings, referred to herein, in which—

Fig. 1 is a side elevation of a shoe broken away to show the elevating member and counter extension;

Fig. 2 is a vertical cross-section substantially on the line 2—2 of Fig. 1 looking in the direction indicated by the arrows in that figure;

Fig. 3 is a perspective inside view of the extension strip as applied to a shoe;

Fig. 4 is a view similar to Fig. 3 showing a modification;

Fig. 5 is a vertical section on the line 5—5 of Fig. 4; and

Fig. 6 is a plan of the extension strip as it is made and sold for application to the shoes.

The extension strip 1 is formed of two long, flat, curved pieces of leather (Fig. 6) joined at their shorter edges by a seam 2 and both pieces being in two sections joined by a flattened seam 3, and the strip made of the united pieces having one or more lace-eyelets 8, according to its width, arranged to correspond in spacing with the eyelets of the shoe. The longer edges of the pieces are free and are skived, as shown at 4, to reduce the thickness of the strip along this edge so that the edge may be inserted between the outer leather 5 and the lining 6 of the shoe at the top edge of the counter (Figs. 2 and 4) and upper vamp—which in low shoes are usually in one piece—and united therewith, by stitching 7 running through all these parts, without producing a foot-irritating ridge or bead.

It will be noted that the extension strip 25 shown—which is full size for a number 10 shoe with one inch elevation—in flat plan (Fig. 6) is at its inner edge approximately an arc of a circle drawn on a radius of about four inches, the said arc cutting the middle and ends of said edge but clearing the intermediate portions, which are shaped or fashioned to conform to the contour of the foot and avoid rubbing the swell below the wearer's ankle. The outer edge of the strip is similarly curved on a radius of 30 five inches, and as circles vary according to pi and the strip is approximately two-fifths of a circle, the outer edge is approximately one and one-fourth inches longer than the inner edge. If the width of the strip is greater the difference will, of course, be greater and if less the difference will be less, but the difference will always be in proportion to the width of the strip and the decrease from outer to inner edge will be uniform throughout. This means that the 35 opening at the top of the shoe which surrounds the foot just below the ankle when the strip is applied in vertical position will be approximately the same for all elevations if the shorter edge is of the same length and the longer edge is 40 cut back on a bevel at the front or cut out on a V at the back to compensate for the increased length of the arc, as indicated by dotted lines in Fig. 6. It will therefore fit the foot of the average and usual wearer—small variations being 45 compensated for in lacing—and hold the shoe on

50 55

the foot. Should any small adjustment be required, however, the seam 3 at the back may be taken in or let out for that purpose. Thus, a rule of the thumb has been discovered by following which the extension of the counter may always be accomplished without impairing the fit of the shoe.

The foot elevating insert 10 is preferably made of cork or other slightly elastic material and is shaped to fit the heel and arch of the normal foot. It can, however, be shaped to fit abnormal or deformed feet, and its top cover 11 may extend to the toe of the shoe. This elevating member is preferably sheathed at bottom and sides in light flexible leather, as indicated at 12, and is cemented to the top of the inner sole of the shoe to which its bottom conforms. It has a raised waist portion 13 to support the instep arch of the foot, since the foot is elevated to a greater or less extent above the normal instep supporting portion of the shoe. The elevating member 10 has its greatest elevation beneath the heel and is tapered gradually toward the ball of the foot, where it terminates, so that the ball of the foot and the metatarsal and phalangeal portions thereof occupy approximately their normal position in the shoe. The counter and vamp portion of the shoe is represented at 14, the toe at 15, sole at 16 and heel at 17, all of which are of usual and ordinary construction, as are also the lace-eyelets 18.

In the modification of Figs. 4 and 5, the counter extending strip 1 is connected with the elevating insert 10 by means of a tongue 20 having a laterally extending portion 21 at its top and portions 22 and 23 at its bottom, preferably of fabric, adapted to extend down behind and under the said elevating member and to be secured by the cement which unites the latter to the shoe insole. It is also preferably cemented or otherwise secured to the underside of the insert 10, the connection being a tacky cement or other connecting means which will permit exact adjustment of the strip 20. Another purpose is served by this tongue when the laterally extending portion is cemented to the extension strip 1 from the top to a point just above the skiving, since it gives the shoemaker an accurate gage at the back of the depth to which the said strip is to be inserted between the layers of the counter at the top, after he has opened the top seam of the shoe. At the front this depth can be accurately gaged by the eyelets and also by leaving the top and front seam closed up to the proper point.

The stitches 7 are run through the top of the outer material 5 and the lining 6 and the skived portion of the extension strip between them, also through the portion 21 of the non-slip connecting tongue (Fig. 4), and replaced the usual stitching around the top of the shoe. Stitches 9 also extend through the strip and the tongue around the top edge and down to the stitches remaining in the front flap between the eyelets and the edge thereof, and where they join these latter stitches also extend through the original outer ply and lining (Fig. 1). The tongue 20 may also be secured to the lining at the wheel by stitching or cement, and a strong cement is also usually applied between these outer and inner plies and the lower edge of the extension strip before the stitches 7 are made.

In order to meet the demands of customers who desire to have elevating inserts incorporated in their shoes—either old or new—the dealer keeps on hand a set of these inserts and also of the ex-

tension strips in plain leather or dyed black and different shades of tan, or the manufacturer or jobber supplies them on order. They also keep on hand white extension strips. If desired, they may dye the extension strips to match the color of the shoe, and if they do this the non-slip tongue member may be attached to the extension strip after the latter is dyed, as this member is of rubberized material or provided with an inner rubber or rubberized cover, as indicated in Fig. 4. The extension strip should be in width about equal to the thickness of the elevating insert or a little less. For elevations not over one-half inch no extension strip is needed, particularly where a non-slip device is applied to the shoe down the back-stay portion inside, and in this case, the retail dealer may stock the non-slip devices unattached to the extension strip and secure them thereto when desired in his shoe repair department or have them so secured by a local repair shop. The wearer may also purchase the desired inserts and extensions of the manufacturer or dealer and have them applied to his shoes by a repair shop.

It will thus be apparent that all the improvements make provision for all contingencies arising in connection with the use of elevating inserts in ordinary ready-made shoes. Various modifications in the exemplary embodiment of the improvements here shown and described, may be made without departing from the scope of the invention.

What I claim is:

1. In a foot elevating device, in combination with an insert of substantial thickness adapted to be positioned inside a shoe on the inner sole and at the instep arch and heel portion thereof and to elevate the foot of the wearer in the shoe, a separate counter extending member comprising a long relatively narrow strip of strong, pliable material detached from but adapted to be secured around the upper edge of the top of a shoe in which the insert is placed, to support itself in position extending above the said top and to substantially surround the unlaced top opening of the shoe, the width of said strip corresponding approximately to the thickness of said insert to compensate for the elevation of the foot by the latter.

2. In a foot elevating device, in combination with an insert of substantial thickness adapted to be positioned inside a shoe on the inner sole and at the instep arch and heel portion thereof and to elevate the foot of the wearer in the shoe, a separate counter extending member comprising a long relatively narrow strip of strong, pliable material detached from but adapted to be secured around the upper edge of the top of a shoe in which the insert is placed, to support itself in position extending above the said top and to substantially surround the unlaced top opening of the shoe, the width of said strip being at least sufficient to compensate for the elevation of the foot by said insert.

3. In a foot elevating device, in combination with an insert of substantial thickness adapted to be positioned inside a shoe on the inner sole and at the instep arch and heel portion thereof and to elevate the foot of the wearer in the shoe, a separate counter extending member comprising a long relatively narrow strip of strong, pliable material detached from but adapted to be secured around the upper edge of the top of a shoe in which the insert is placed, to support itself in position extending above the said top and to sub-

stantially surround the unlaced top opening of the shoe, the width of said strip being at least sufficient to compensate for the elevation of the foot by said insert, said strip being formed flat on a curve having a length substantially equal to the circumference of the upper edge of the shoe when it is applied thereto in upright position at its inner edge and its outer edge of greater length and adapted to be secured to said top.

4. In a foot elevating device, in combination with an insert of substantial thickness adapted to be positioned inside a shoe on the inner sole and at the instep arch and heel portion thereof and to elevate the foot of the wearer in the shoe, a separate counter extending member comprising a long relatively narrow strip of strong, pliable material detached from but adapted to be secured around the upper edge of the top of a shoe in which the insert is placed, to support itself in position extending above the said top and to substantially surround the unlaced top opening of the shoe, the width of said strip being at least sufficient to compensate for the elevation of the foot by said insert, said strip being formed flat on a curve having a length substantially equal to the circumference of the upper edge of the shoe when it is applied thereto in upright position at its inner edge and its outer edge of greater length and adapted to be secured to said top, said outer edge being reduced in length by cutting out tapering portions of the strip.

5. In a foot elevating device, in combination with an insert of substantial thickness adapted to be positioned inside a shoe on the inner sole and at the instep arch and heel portion thereof and to elevate the foot of the wearer in the shoe, a separate counter extending member comprising a long relatively narrow strip of strong, pliable material detached from but adapted to be secured around the upper edge of the top of a shoe in which the insert is placed, to support itself in position extending above the said top and to substantially surround the unlaced top opening of the shoe, the width of said strip being at least sufficient to compensate for the elevation of the foot by said insert and means for connecting said insert and strip.

6. In a foot elevating device, in combination with an insert of substantial thickness adapted to be positioned inside a shoe on the inner sole and at the instep arch and heel portion thereof and to elevate the foot of the wearer in the shoe, a separate counted extending member comprising a long relatively narrow strip of strong, pliable material detached from but adapted to be secured around the upper edge of the top of a shoe in which the insert is placed, to support itself in position extending above the said top and to substantially surround the unlaced top opening of the shoe, the width of said strip being at least sufficient to compensate for the elevation of the foot by said insert and means for connecting said insert and strip, said means being a flat extending piece at the heel of said parts having an exposed non-slip surface.

7. In a foot elevating device, in combination with an insert of substantial thickness adapted to be positioned inside a shoe on the inner sole and at the instep arch and heel portion thereof and to elevate the foot of the wearer in the shoe, a separate counter extending member comprising a long relatively narrow strip of strong, pliable material detached from but adapted to be secured around the upper edge of the top of a shoe in which the insert is placed, to support itself in

position extending above the said top and to substantially surround the unlaced top opening of the shoe, the width of said strip being at least sufficient to compensate for the elevation of the foot by said insert and means for connecting said insert and strip comprising a flat piece of material connected with both and its length between them being less than the distance from the top of the insert to the top of the shoe.

- 10 8. In a foot elevating device, in combination with an insert of substantial thickness adapted to be positioned inside a shoe on the inner sole and at the instep arch and heel portion thereof and to elevate the foot of the wearer in the shoe,
- 15 15 a separate counter extending member comprising a long relatively narrow strip of strong, pliable material detached from but adapted to be secured around the upper edge of the top of a shoe in which the insert is placed, to support itself in
- 20 20 position extending above the said top and to substantially surround the unlaced top opening of the shoe, the width of said strip being at least sufficient to compensate for the elevation of the foot by said insert and means for connecting said
- 23 23 insert and strip, said means being a flat extending piece at the heel of said parts secured to the strip only at the part of the latter which projects above the upper edge of the shoe when said strip is connected with said shoe.

30 9. In a foot elevating device, in combination with an insert of substantial thickness adapted to be positioned inside a shoe on the inner sole and at the instep arch and heel portion thereof and to elevate the foot of the wearer in the shoe, a separate counter-extending member comprising a long relatively narrow strip of strong, pliable material detached from but adapted to be secured around the upper edge of the top of a shoe in which the insert is placed, to support it-
35 40 self in position extending above the said top and to substantially surround the unlaced top opening of the shoe, the width of said strip corresponding approximately to the thickness of said insert to compensate for the elevation of the foot by the latter, said insert having skived lower edges adapted to be inserted between the outer leather and the lining of the shoe at the top edge of the shoe and secured thereto by stitches running through all three parts.

50 10. In a foot elevating device, in combination
with an insert of substantial thickness adapted
to be positioned inside a shoe on the inner sole
and at the instep arch and heel portion thereof
and to elevate the foot of the wearer in the shoe,
55 a separate counter extending member comprising
a long relatively narrow strip of leather de-
tached from but adapted to be secured around
the upper edge of the top of a shoe in which the
insert is placed, to support itself in position ex-
tending above the said top and to substantially
60 surround the unlaced top opening of the shoe,
the width of said strip being at least sufficient
to compensate for the elevation of the foot by
said insert.

65 11. In a foot elevating device, in combination
with an insert of substantial thickness adapted
to be positioned inside a shoe on the inner sole
and at the instep arch and heel portion thereof
and to elevate the foot of the wearer in the shoe,
70 a separate counter extending member comprising
a long relatively narrow strip composed of
two plys of strong, pliable material connected
along their upper edges only detached from but
adapted to be secured around and within the
75 upper edge of the top of a shoe in which the

insert is placed, to support itself in position extending above the said top and to substantially surround the unlaced top opening of the shoe, the width of said strip being at least sufficient to compensate for the elevation of the foot by said insert, said strip being formed flat on a curve having a length at its inner edge substantially equal to the circumference of the upper edge of the shoe when it is applied thereto in upright position and its outer edges skived and of greater length and adapted to be inserted within said top.

12. In a foot elevating device, in combination with an insert of substantial thickness adapted to be positioned inside a shoe on the inner sole and at the instep arch and heel portion thereof and to elevate the foot of the wearer in the shoe, a separate counter extending member comprising a long relatively narrow strip of strong, pliable material detached from but adapted to be secured around the upper edge of the top of a shoe in which the insert is placed, to support itself in position extending above the said top and to substantially surround the unlaced top opening of the shoe, the width of said strip being at least sufficient to compensate for the elevation of the foot by said insert, said strip being formed flat approximately on arcs of different radii drawn from a common center and having a length at its inner edge substantially equal to the circumference of the upper edge of the shoe when it is applied thereto in upright position and its outer edge of greater length and adapted to be secured to said top.

13. A shoe, a foot elevating insert of substantial thickness upon the inner sole therein, a separate extension strip secured upon the upper edge of the counter thereof of a width approximately equal to the thickness of the insert of material similar to that of the shoe top and matching it in color, said strip having an eyelet therein in line with the lacing eyelets of the shoe.

14. A shoe, a foot elevating insert of substantial thickness upon the inner sole therein, a separate extension strip secured upon the upper edge of the counter thereof of a width approximately equal to the thickness of the insert of material similar to that of the shoe top, and a flat strip or strap connecting the said extension strip or tongue and the insert at the inside of the heel portion of the shoe.

15. In a foot elevating device an extension member to be applied to the upper edge of the top of a shoe and to extend above said top to compensate for the elevation of the foot of the wearer by a foot raising insert on the bottom of the shoe, said extension member comprising a strip of material similar to that of the shoe top composed of strong, pliable self-supporting material curved and shaped along its upper edge to approximate the upper edge of the shoe to which it is applied and having a length approximately equal to that of the said upper edge of the shoe and having its lower edge skived to a

depth sufficient to be attached to said upper edge of the shoe by a line of stitching running through both thus reducing the thickness of the said connected edges.

16. The method of fitting a shoe with a foot elevating device which consists in providing the rear portion of the shoe inside with an insert or insole having a thickness substantially equal to the elevation desired then applying around the upper edge of the shoe counter a strip of material matching the material of the adjacent part of the shoe and having a width approximating the thickness of the insert and provided with lace-eyelets corresponding and in line with the lace-eyelets of the shoe, said strip being preformed by cutting out a flat curved piece of material having one edge substantially equal to the circumference of said upper edge and the other edge of the strip longer but curved on substantially an extension of the radius on which the first edge is cut drawn from a common centre:

17. The method of fitting a shoe with a foot elevating device which consists in providing the rear portion of the shoe inside with an insert or insole having a thickness substantially equal to the elevation desired then applying around the upper edge of the shoe counter a strip of material matching the material of the adjacent part of the shoe and having a width approximating the thickness of the insert and provided with lace-eyelets corresponding and in line with the lace-eyelets of the shoe, said strip being preformed by cutting out a flat curved piece of material having one edge substantially equal to the circumference of said upper edge and the other edge of the strip longer but curved on substantially an extension of the radius on which the first edge is cut drawn from a common centre then cutting out beveled portions of the strip to reduce the length of the second edge and uniting the edges of the cut.

18. The method of fitting a shoe with a foot elevating device which consists in providing the rear portion of the shoe inside with an insert or insole having a thickness substantially equal to the elevation desired then applying around the upper edge of the shoe counter a strip of material matching the material of the adjacent part of the shoe and having a width approximating the thickness of the insert and provided with lace-eyelets corresponding and in line with the lace-eyelets of the shoe, said strip being preformed by cutting out a flat curved piece of material having one edge substantially equal to the circumference of said upper edge and the other edge of the strip longer but curved on substantially an extension of the radius on which the first edge is cut drawn from a common centre then uniting the insert and strip by a connecting piece secured to the heel portions of both and providing said piece with a friction increasing surface.

WILLIAM M. SCHOLL.
